QUIET TYPEWRITER

Charles Schroder, West Hartford, Conn., assignor
to Underwood Corporation, New York, N. Y., a
corporation of Delaware

Application December 29, 1950, Serial No. 203,289

11 Claims. (Cl. 197—186)

This invention relates to quiet typewriters, and has for its principal object to provide a typewriter in which the sounds made incident to the various operations of its mechanism are reduced to a noise level materially below that heretofore obtained.

Another object of the invention is to provide a novel combination of typewriter-base, mechanism-supporting frame, mask and muffler-casing or enclosure therefor in such a cooperative relation as to reduce to a substantial extent the noises of various frequencies and magnitudes resulting from the different impacts incident to operation of the typewriter mechanism.

The invention is in the nature of an improvement over the invention described in my copending application, Serial No. 134,703, filed December 23, 1949, now U. S. Patent No. 2,639,020, to the end that the noise of the typewriter is reduced to a negligible level and the operation is so quiet as to show an appreciable lowering of the noise level to a point under that of the present so-called "noiseless" typewriters. For example, in recent comparative tests made in an office where the usual noise level of the room was about an average of that in various offices, the noiseless typewriter was audible at a distance of about five feet, whereas the typewriter of the present invention was audible only at about two and a half feet from the machine.

Other objects will be in part obvious and in part particularly pointed out as the following description of one embodiment of the invention proceeds.

In the drawings wherein is represented one of the various possible embodiments of the invention:

Figure 1 is a front elevational view of the quiet typewriter embodying the invention, portions being broken away to reveal various structural features.

Figure 2 is a view in cross section taken substantially along the median plane indicated by line 2—2 of Figure 1 with portions being broken away to show certain of the vibration-absorbing elements in central section.

Figure 3 is a view in cross section similar to Figure 2 but taken on a line 3—3 of Figure 1, and

Figure 4 is a wiring diagram of the circuit connections to the light and motor of the typewriter.

Referring now to the drawings and particularly to Figure 2, the entire typewriter with the exception of its keyboard is enclosed within a casing or enclosure generally indicated at 7. The casing includes a lower section 8 and an upper section or cover 9 hinged thereto for opening to provide access to the typewriter primarily for purposes of inserting and removing the work sheet,

as well as making erasures in the typing. The typewriter forming the embodiment of the invention illustrated, is substantially like that shown and described in my copending application, Serial No. 134,703, filed December 23, 1949, now U. S. Patent No. 2,639,020. Said pending application is directed to certain features embraced within the usual mask or shell of the typewriter for damping or deadening sound vibrations. In the present invention these features cooperate with the outer enclosure or casing 7 to accomplish the substantial overall noise reductions in the operation of the typewriter.

The typewriter comprises a metal base member 10 of open rectangular form which has fixed thereto a hand rail 11 surrounding and framing the keyboard of the typewriter. At each inner corner of the base an ear 12 is provided to which is attached a foot 13. Each foot 13, of which there are preferably four, is received in a recess or cavity 14 formed in the bottom wall of the lower section of casing 7. Each foot 13 may be constructed substantially as shown in the Lentz Patent No. 2,549,692, issued April 17, 1951, and comprises a metal cap 15, a body of resilient material 16 such as rubber or neoprene, which has a reduced upper portion fitting the cap 15, and an enlarged base portion 17. The base portion 17 fits fairly snugly into the recess 14.

Each ear 12 has a recess 20 in which are mounted diaphragms 21, Fig. 2, on which a skeleton frame 22 is supported. The diaphragms are composed of a central metal tube 23 to which is vulcanized a web 24 of sound deadening material such as rubber and having a size and density in proportion to the load supported thereby. The web 24 is preferably circular and has a metal band vulcanized to its periphery. Each of the diaphragms is pressed into the recess 20 at each corner of the base 10, and a screw 26 secures the frame 22 to the base at the four corners. The screws 26 project through the metal tubes 23 and are threaded into metal pieces 27 secured to the lower edges of the frame.

The skeleton frame 22 has two side walls 28 connected by a number of cross bars secured at their ends to the side walls to form the complete frame. These include a cross bar 30 which provides a support for an electric motor 31 which, by its transmission devices indicated generally at 32, drives the various operating mechanisms of the typewriter. Another cross bar 33 provides the mounting for the platen carriage 34. Other cross bars 35, 36, and 37 are provided, the first two respectively supporting the key levers 38 and the type-bar actuating arms 39. Other units and

mechanisms, not shown, are also supported on the skeleton frame 22. These include the usual ribbon spools and associated ribbon feed and reversing mechanism, the ribbon vibrating mechanism, mechanisms for case shifting, letter feeding the carriage, and power-return of the carriage.

It will be noted that all of the working parts of the typewriter are supported on the skeleton frame 22, and this frame in turn is supported solely on the sound damping diaphragms 21. The resilience of the mounting afforded by the diaphragms 21, under the vibratory effect of rapid operation of the various typewriter mechanisms, has the tendency to set up mechanical vibrations of the frame 22, which are objectionable particularly because they result in a vibratory movement or tilting of the carriage. To obviate these difficulties means are provided, as described in my said copending application, for limiting the amplitude of these vibrations or movements. Such means comprises adjustable cushion-stop devices 41, one at each side of the typewriter, adjacent the side walls 23. Each stop device includes a screw 42 threaded in an ear 43 on the base 10, the head of the screw having a coil spring adapted to engage, but normally free of, a lug 44 at each end of the cross bar 37. The screws 42 are adjusted so that there is a slight clearance between the spring end and lug 44. The clearance is such as not to allow the vibrations or movements to exceed the maximum permissible amplitude. Thus, as the frame 22 sets up mechanical vibrations or tilting movements, these are checked and regulated to an extent to greatly minimize the objectionable results.

The skeleton frame 22 and the mechanisms supported thereby are covered and enclosed in large part by a mask which, in relation to the casing or outer-enclosure 7, forms an inner shell closely encasing the operating mechanisms of the typewriter. This mask comprises a front wall 46 which, as shown in Fig. 2, curves upwardly toward the rear to blend into a top wall, and further comprises a rear wall 47 and two side walls 48, one of which is shown in Fig. 1. As indicated at 49, Figs. 1 and 2, the walls 46, 47, 48 of the mask are lined with a layer of sound absorbing material such as felt.

As afore-mentioned, the upper section or cover 9 of the casing 7 is hinged at 51 along a rear juncture of the lower and upper sections 8, 9. Upon being released by operation of a latching device later described, the cover 9 is automatically raised by a spring-powered raising device 52, see Fig. 3, which is substantially like that fully disclosed in the Lindburg Patent No. 1,603,781. This device comprises a bracket 53 secured to the lower section 8 and holding a shaft on which a slotted arm 54 is mounted for rocking movement. A torsional spring 55 surrounding said shaft tends to swing the arm 54 in a clockwise direction. A tension-adjusting device in the form of a worm-and-gear mechanism 56, 57 and arranged between the arm 54 and the spring 55, affords adjustment of the force of spring 55 so that it is just ample to raise the cover without harsh action. The arm 54 has a slot in which a post 58 operates, the post being mounted on the cover 9 to transmit the raising force of the arm 54 thereto. As the cover 9 reaches its fully open position, as determined by the post reaching the leftward end of the slot in arm 54, a pair of leaf springs converging toward each other at said end impart a snub-

bing action to post 58, which brings the cover quietly to a stop at open position.

Referring to Fig. 3, the cover-latching device comprises a bracket 60 secured to the cover 9 and on which is hook-shaped latch 61 is pivoted. A spring 62 tensions latch 61 to swing clockwise to a position determined by a stop 63 on said bracket. To hold the cover 9 in its closed position, the latch 61 hooks under a lug 64 on the lower section 8. The latch 61 is swung rightward to release its hook from lug 64 by the camming action of a release bar 65. The upper end of said bar has a bevel adapted to coact with a stud 66 on the latch 61. At its upper end the release bar 65 is slidably guided in a slotted member 67 and its lower end is articulated to a lever arm 68. The arm 68 at its leftward end is secured to a stub shaft 69 which is journaled in and projects through a wall portion 70 of the lower section 8. At its other end the stub shaft 69 has secured thereto a lever 71 which carries a palm key 72. For convenient access by the typist, the palm key 72 is arranged adjacent the typewriter keyboard just outside the hand rail 11. Depressing the palm key 72 will cause lever 71 and arm 68 to rock about the axis of stub shaft 69, and thus raise the release bar 65 to cause its beveled end to cam the latch 61 out of engagement with lug 64. Upon release of said latch the action of the cover-raising device 52 will cause the cover 9 to be quickly and silently raised. For convenience in closing the cover against the force of the raising device 52, a handle 73 is provided at the front of the cover.

As illustrated in Fig. 1, the lower section 8 has a width, from its bottom upward a major portion of its depth, which is slightly greater than the width of the machine at the base 10 and mask side walls 48. The space between the side walls 48 and the adjacent walls of the lower section affords room for grasping the machine for lifting it out. The upper portion of section 8 and the entire upper section 9 are of such width end to end as to allow the platen carriage 34 to travel the full extent in each direction. By keeping the width of a major portion of the lower section to about a minimum as shown, the typewriter fits readily in the usual place on standard secretarial desks.

The adjoining edges of the lower and upper sections 8, 9 meet in abutting relation. To assure a tight, soundproof closure all said edges are bound by a rubber or flexible plastic strip 75 having a channel which straddles and closely fits the marginal portions of each section. The two flanges of the strip 75 are connected by a curved wall 76, and a web 77 adjacent said wall and spanning said flanges forms a shallow tubular section with wall 76. This tubular section affords a resilience that assures a soundproof juncture with the opposite edge strip 75 or with another surface, as later mentioned.

It may be here noted with reference to Figs. 1 and 2 that the front wall 46 of the typewriter mask or inner shell forms the wall of the muffler casing 7 at that region. This has the advantage of making certain control elements in wall 46 accessible without complicating the structure of the casing 7 in order to have said elements brought out thru a second wall. These control elements include a bichrome ribbon selector knob 80 and a motor switch knob 81 by which the motor 31 is controlled. It should also be noted that the mask wall 46 ranges upwardly beyond the height of the lower casing section 8 and,

where it bends rearward to converge with the top wall of the mask, is engaged directly by the upper section or cover 9, as shown clearly in Fig. 2. The curvature of the front wall 46 at the region where the cover 9 joins it, enables arranging the adjacent portion of the cover in a tangential relation to said curvature. This arrangement accommodates a greater degree of tolerance as to the dimensions of the typewriter mask at this region and allows some variance in the fore-and-aft location of the typewriter in the casing 7 and the form and shape of the cover 9 at said region. In this regard it should be noted that the proper closure of the cover 9 along its front edge requires, one, that it meet and engage the edges of the lower section in abutting relation with such accuracy as to afford a tight soundproof juncture and, two, that it also conform to the somewhat variant contour and slightly variable location of the front wall 46 of the inner shell or mask. These conditions are best met by arranging the adjacent cover portion in tangential or overlying relation to the front wall 46. As shown in Fig. 2, a layer of felt 83 or other resilient material may be used to seal the juncture of the cover 9 and front wall 46. As shown in Fig. 1, the strip 75 is also used on the cover edge which overlies front wall 46 of the mask. Although of no practical purpose at this region, it forms a continuing border at the cover edge extending uninterrupted across the front of the casing 7, which enhances its general appearance.

As shown more clearly in Fig. 2, the front wall 46 of the typewriter mask or inner shell is substantially forward of the adjacent front area 84, Fig. 1, of the casing 7. This has the advantage, in appearance, of minimizing the depth of the casing 7 from front to back. From the practical standpoint, it puts the two side edges 85 of said front area at a plane far enough back from the mask front wall 46 to assure that said side edges engage a flat, even area of each mask side wall 48. In this regard it will be noted that the vertical front corners of the mask are preferably well rounded. The strip 75 on the top edge of the lower section 8 is mitered at the corner where said edge meets the mask side wall 48 and strip 75 thence continues down the vertical edge. The tubular portion of this vertical strip, in pressure contact with the mask side wall affords a soundproof joint and yet enables easy placement or removal of the typewriter unit from the outer casing 7.

As before mentioned, the skeleton frame 22, during rapid operations of the typewriter including banking of the carriage in tabulating or in return runs, vibrates and tilts laterally, due to the resilience and yielding action of the diaphragms 21. It will be recalled that the skeleton frame and the mechanisms supported by it are enclosed in large part by the mask 46, 47, 48. It follows, therefore, that these vibrations or movements are confined to within said mask and the attendant noises, being thus isolated substantially to the skeleton frame 22, are not transmitted to the mask and thence to the casing 7. And the mask, not subject to such vibratory movements, may have a snug fit and tightly jointed assembly with the outer enclosure or casing 7. For example, the fit of the mask, where its side walls 48 are met by the edges 85 of the casing front walls, may be snug and tight so as to assure a soundproof joint or seal. Likewise, the engagement of the cover 9 with the mask 75

may be close to secure a maximum seal against emission of noise. This is an important and distinguishing feature of the present invention in comparison with prior attempts in this direction and has particular importance in obtaining quiet operation of so-called electric typewriters.

Substantially all the interior surfaces of the casing 7 have a lining of sound-insulating material 82 affixed thereto. A number of such materials having either a porous or fibrous character may be used as a suitable acoustical insulation; however, good results are obtained by a matted glass wool material known commercially as Fiberglas. This material in a one inch free thickness is recommended, the same to be compressed to about $\frac{1}{2}$ inch thickness when installed. This sheet material may be cut into mats to fit the various separate areas of the casing 7 and may be covered with a cloth material if desired. Each mat thus formed may be secured, as by cementing, to the interior surfaces of the casing 7.

As shown in Fig. 2, the bottom area of the lower section 8 has a layer 86 of sound-insulating material of lesser thickness applied thereto, a cotton felt being found suitable for this purpose. The lower surface of said area may also have a layer of felt applied thereto.

To prevent the leading or trailing edges of the paper on the platen carriage 34 from catching the insulating material 82 or its cloth covering, the casing cover 9 has a sheet metal deflector 87 lining same. This deflector covers the area above and to the rear of the platen carriage 34, and provides a trough 88 which prevents the paper from becoming mutilated by engaging projections at the back of the typewriter as the carriage travels. The trough 88 extends the full length of carriage travel in each direction and thus guides the paper smoothly over the shallow end portions of the lower casing section 8. The deflector 87 is secured to the cover 9 by screws threaded into posts 89 on the cover, a rubber washer being inserted between the screw head and the deflector.

The typist observes the progress of the work through a window 90 provided in the cover section 9. To prevent the transmission of sound waves therethrough, said window preferably comprises two layers of glass separated by marginal strips. Since the usual room illumination is shaded from the typing sheet by the casing cover 9 in its closed position, the typewriter provides its own illumination, preferably in the form of a fluorescent light 91. The light 91 is mounted by suitable means on the interior of the cover 9, in a position immediately above and slightly forward of the typewriter platen and preferably co-extensive with the window 90. A switch 92, later described, is mounted on the cover 9 and controls the current to the light 91.

For supplying electric current to both the motor 31 and the fluorescent light 91, the typewriter unit with casing 7 may be wired in accordance with the circuit shown in Fig. 4, assuming that alternating current is used. The switch 92 is of the usual well-known type used where the starting of the fluorescent bulb is effected manually by manipulating the switch. The control element in this type of switch is manipulatable to three positions, namely "off," "on," and "start," progressing from left to right in the order given. This switch comprises two normally open switches as shown, both of which are closed when the control element is moved to "start" position,

7
and the upper one of which stays closed when the said element is moved to "on" position. Although the motor has its own switch 81, it is preferable to have the switch 92 control both the fluorescent light and the motor, so that the typist need usually operate only the one switch. From the circuit wiring between the fluorescent bulb 91 and switch 92, connections 93 and 94 are made, by which current is directed to the motor 31 when switch 92 is either in its "start" or "on" position, assuming motor switch 81 to be closed. The circuit to the fluorescent light 91 includes the usual ballast 95 and condenser 96.

To avoid running an extension cord through the wall of the casing 7, for supplying electric current to the light 91 and motor 31, an adaptor fixture 98, Fig. 3, is provided. Said fixture comprises an outlet box 99 attached to a rear wall of the lower casing section 8, which wall has an opening 100 in which the receptacle unit of an extension cord, not shown, is inserted for coupling to a two-prong connector 101 secured in the box. A receptacle 102 at the front of the box 99 is adapted to receive a plug 103 of an extension cord, the wires of which are connected to the motor 31, one wire including the switch 81. From the terminals of the two prongs of connector 101 connections are made to the fluorescent light 91 and its switch 92, as well as the ballast and condenser units 95 and 96, said connections being made as shown in the wiring diagram, Fig. 4. The plug and receptacle connection 102, 103 afforded by the adaptor fixture 98 enables convenient detachment of the extension cord to the typewriter motor and thus facilitates assembly and removal of parts for service or replacement. The provision of the two-prong connector 101 enables detachment of the extension cord from the entire typewriter unit when desired. Primarily, however, the adaptor fixture 98 enables making the necessary connections from the current supply to the casing and from said casing to the typewriter motor 31 and fluorescent light circuit without requiring an actual opening in the casing 7 thru which the extension cord may extend. Thus, the full extent of the quieting effect of the casing 7 is assured by the adaptor fixture 98 in that said fixture obviates the necessity for any thru opening in the casing to afford a passage for the usual extension cord.

The following table shows the results of noise level tests conducted on the three typewriters noted. In tests A and B the same typewriter was used, except that in test B the typewriter was constructed in accordance with the present invention. In all three tests the typewriters were supported on a stand. The various machine operations given in the table are self explanatory, except "Regular Write" which consists of typing two lines of text, the text being the same in each instance. All readings are in decibels.

	Test A	Test B	Test C
	Electric Typewriter, Appl., Ser. No. 134,703	Electric Typewriter, present Application	Manual Noiseless Typewriter
Regular Write	Db 67	Db 56	Db 61
Case Shift	58	52	63
2" Tabulation	66	60	62
Space Bar	62	54	59
Line Space	71	62	62
Back Space	59	52	60
Tabbing	42	41	

8
A comparison of the readings in tables A and B shows the great reduction in noise level afforded by the improvements of the present invention over that of the typewriter of the application Serial No. 134,703. Of particular significance is the drop of 11 decibels in the "Regular Write" test readings.

Also of significance in showing the substantial noise reductions of the present invention is a comparison of tables B and C. Except for line-spacing, all operations show an appreciable lowering of the noise level in the present invention from that of the noiseless typewriter.

In making these comparisons it should be noted that the decibel unit is a ratio or logarithmic value and, as such, should not be compared merely on the basis of numerical quantity differences. While these differences in the decibel readings are in most cases appreciable, the audible differences perceptible to the human ear are far more impressive.

What is claimed is:

1. In a typewriting machine, in combination, typing instrumentalities including a keyboard, a set of type bars and a platen carriage, a skeleton frame supporting said typing instrumentalities, a base, resilient sound-damping means mounting said frame on the base, said frame being capable of vibratory and tilting movements as an incident to rapid operations of the machine and due to the resilience of said mounting means, a mask substantially enclosing the typing instrumentalities excepting the keyboard and platen carriage, means supporting said mask in stable relation to said base, a casing having sound-insulating walls and housing said base and said mask and said platen carriage throughout its range of travel but exposing said keyboard, said casing defining an opening thru which said keyboard extends for operation outside the casing, and the edges of the casing defining the sides of the opening having pressure contact with said mask and base.

2. In a typewriting machine, in combination,

typing instrumentalities including a keyboard, a set of type bars and a platen carriage, a skeleton frame supporting said typing instrumentalities, a base having foot means, resilient sound-damping means mounting said frame on the base, said frame being capable of vibratory and tilting movements as an incident to rapid operations of the machine and due to the resilience of said mounting means, a mask substantially enclosing the typing instrumentalities excepting the keyboard and platen carriage, means supporting said mask in stable relation to said base, a casing having sound insulating walls and housing said base and said mask and said platen carriage throughout its range of travel but exposing said keyboard, said casing defining an opening thru which said keyboard extends for operation outside the casing, and the edges of the casing defining the sides of the opening having pressure contact with said mask and base.

3. In a typewriting machine, in combination, typing instrumentalities including a keyboard, a set of type bars and a platen carriage, a skeleton frame supporting said typing instrumentalities,

a base, means mounting said frame on the base comprising a plurality of sound-damping diaphragms, said frame being capable of vibratory and tilting movements as an incident to rapid operations of the machine and due to the resilience of said diaphragms, a mask

4. In a typewriting machine, in combination,

typing instrumentalities including a keyboard, a set of type bars and a platen carriage, a skeleton frame supporting said typing instrumentalities, a base, means mounting said frame on the base comprising a plurality of sound-damping diaphragms, said frame being capable of vibratory and tilting movements as an incident to rapid operations of the machine and due to the resilience of said diaphragms, a mask

supported by said base and substantially enclosing the typing instrumentalities excepting the keyboard and platen carriage, a casing having sound insulating walls and housing said base and said mask and said platen carriage throughout its range of travel but exposing said keyboard, said casing defining an opening thru which said keyboard extends for operation outside the casing, and the edges of the casing defining the sides of the opening having pressure contact with said mask and base.

4. In a typewriting machine, in combination, typing instrumentalities including a keyboard, a set of type bars and a platen carriage, a skeleton frame supporting said typing instrumentalities, a base, resilient sound-damping means mounting said frame on the base, said frame being capable of vibratory and tilting movements as an incident to rapid operations of the machine and due to the resilience of said mounting means, a mask supported by said base and substantially enclosing the typing instrumentalities excepting the keyboard and platen carriage, a casing having sound-insulating walls and housing said base and said mask and said platen carriage throughout its range of travel, said casing defining a front opening, the forward portion of said mask protruding thru said opening, and the edges of said casing defining the sides of the opening having a pressure contact with the side areas of said mask to form a soundproof joint at said edges.

5. A soundproof casing for housing a typewriter or like machine for quiet operation, the typewriter having a keyboard, a platen carriage and a mask, the mask substantially enclosing the operating mechanisms of the typewriter except the keyboard and carriage, the mask having a front wall and top wall joined by a curved portion, said casing comprising a lower section adapted to receive the typewriter therein and having upstanding walls including a front wall all terminating in a common horizontal plane, the front wall of said lower section defining an opening adapted to admit the typewriter with the front wall of its mask substantially forward of the front wall of the lower section and with the typewriter projecting substantially above the horizontal plane, said casing also including an upper cover section hinged to the lower section and having depending walls meeting the upstanding walls of said lower section in abutting relation, the portion of said cover section over said opening slanting forwardly and downwardly immediately over and in tangential relation to the curved portion of said mask between its front and top walls.

6. In a typewriting machine, in combination, typing instrumentalities including a keyboard, a set of type bars and a platen carriage, a skeleton frame supporting said typing instrumentalities, a base, resilient sound-damping means mounting said frame on the base, said frame being capable of vibratory movements incident to rapid operations of the typewriter and due to the resilience of said mounting means, a mask substantially enclosing the typing instrumentalities excepting the keyboard and platen carriage, said mask having a front wall and a contiguous top wall, a casing having sound-insulating walls and housing said base and said mask and said platen carriage throughout its range of travel, said casing comprising a lower section adapted to receive the typewriter therein and having upstanding walls including a front wall, said front wall defining an opening adapted to admit the

typewriter with the front wall of its mask substantially forward of the front wall of the lower section, said casing also including a hinged upper section having depending walls meeting the upstanding walls of said lower section, the sides of said opening pressing against the side areas of said mask, the portion of said cover section over said opening slanting forwardly and downwardly in close overlying relation to the juncture of the front and top walls of said mask.

7. In a typewriting machine, in combination, typing instrumentalities including a keyboard and a set of type bars and a platen carriage, a skeleton frame supporting said typing instrumentalities, a mask substantially enclosing the typing instrumentalities excepting the keyboard and the platen carriage, means including resilient sound-damping diaphragms supporting said skeleton frame, said frame being capable of vibratory and tilting movements incident to rapid operations of the machine due to the resilience of said diaphragms, means supporting said diaphragms and supporting said mask independently of the skeleton frame, the last said supporting means including foot elements having vibration-absorbing characteristics and yet affording a substantially rigid support, and a casing having a floor and sound-insulating walls and housing said mask and said platen carriage throughout its range of travel, said casing having a front wall opening through which the keyboard and the forward portion of said mask extends, the casing front wall edges which define the sides of the opening having a firm contact with the side areas of the mask to form a soundproof joint at said edges, said foot elements resting on the casing floor and forming the support for the mask within the casing.

8. In a typewriting machine, in combination, typing instrumentalities including a keyboard and a set of type bars and a platen carriage, a skeleton frame supporting said typing instrumentalities, a mask substantially enclosing the typing instrumentalities excepting the keyboard and the platen carriage, means including resilient sound-damping diaphragms supporting said skeleton frame, said frame being capable of vibratory and tilting movements incident to rapid operations of the machine due to the resilience of said diaphragms, means supporting said diaphragms and supporting said mask independently of the skeleton frame, the last said supporting means including foot elements having vibration-absorbing characteristics and yet affording a substantially rigid support, and a casing having a floor and sound-insulating walls and housing said mask and said platen carriage throughout its range of travel, said casing having a front wall opening through which the keyboard and the forward portion of said mask extends, the casing front wall edges which define the sides of the opening having a firm contact with the side areas of the mask to form a soundproof joint at said edges, said casing including a floor having recesses, said foot elements setting in the recesses of the casing floor and forming therewith the only support and locating means for the mask within the casing.

9. In a typewriter, in combination, a skeleton frame having mounted thereon typing instrumentalities including a keyboard and a set of type bars and a platen carriage; means for driving said type bars and for relatively ease shifting the type bars and the platen and for moving the platen carriage, said means comprising a

motor and transmission devices mounted on said skeleton frame; a mask substantially enclosing the driving means and the typing instrumentalities excepting the keyboard and the platen carriage; means including resilient sound-damping diaphragms supporting said skeleton frame; said frame, due to the resilience of said diaphragms, being capable of vibratory and tilting movements incident to rapid operations of the typing instrumentalities; means supporting said diaphragms and supporting said mask independently of the skeleton frame; a casing having sound-insulating walls and housing substantially the entire typewriter excepting the keyboard, said casing having a front wall defining an opening through which said keyboard extends, the front wall edges defining the opening having a firm contact with said mask to form a soundproof joint at said edges, the keyboard having elements for controlling the various operations of the typing instrumentalities including that of moving the platen carriage.

10. In a typewriter, in combination, a skeleton frame having mounted thereon typing instrumentalities including a keyboard and a set of type bars and a platen carriage; means for driving said type bars and for relatively ease shifting the type bars and the platen and for moving the platen carriage, said means comprising a motor and transmission devices mounted on said skeleton frame; a mask substantially enclosing the typing instrumentalities excepting the keyboard and the platen carriage; means including resilient sound-damping diaphragms supporting said skeleton frame; said frame, due to the resilience of said diaphragms, being capable of vibratory and tilting movements incident to rapid operations of the typing instrumentalities; means supporting said diaphragms and supporting said

5 mask independently of the skeleton frame; the last said supporting means including foot elements having vibration-absorbing characteristics and yet affording a substantially rigid support; and a casing having a floor and sound-insulating walls and housing substantially the entire typewriter except the keyboard, said casing having a front wall defining an opening through which said keyboard extends, the front wall edges defining the opening having a firm contact with said mask to form a soundproof joint at said edges, said foot elements resting on the casing floor to support the typewriter in the casing, the keyboard having elements for controlling the various operations of the typing instrumentalities including that of moving the platen carriage.

15 11. A noiseless electric typewriter having a skeleton frame and an electric motor, platen-carriage, type actions and operating keys mounted on said frame, a base having slip resistant feet and a plurality of resilient diaphragms on which the skeleton frame is mounted, mask means for the skeleton frame mounted on the base and comprising walls spaced from the skeleton frame and the said parts mounted thereon, a casing having means for definitely locating the base with the operating keys in front of the casing and having means for sealing the mask when the base is so located, a movable cover for 20 said casing having means for further sealing the mask, and electrical connections from the electric motor to the exterior of the casing.

CHARLES SCHRODER.
